DEFORMABLE PLASTIC DISPENSER

Jerome Gould, Encino, Calif., assignor to Design Properties, Inc., Los Angeles, Calif., a corporation of California

Continuation of application Ser. No. 457,347, May 20, 1965. This application Mar. 1, 1967, Ser. No. 619,871
8 Claims. (Cl. 222—215)

ABSTRACT OF THE DISCLOSURE

This invention relates to a seasoning dispenser which is formed from a pair of oppositely disposed rigid ends and a corrugated body between the ends. Holes are provided in one of the ends to dispense the seasoning. The dispenser is operated by pressing the corrugated portion. This causes the body portion to become collapsed on the corrugations and the opposite end portions to become rotated in opposite directions without deforming the end portions and without changing the distance between the end portions.

This application is a continuation of Ser. No. 457,347, filed May 20, 1965, now abandoned.

This application relates to a plastic dispenser. More specifically, this application relates to a deformable plastic dispenser so constructed that a compressive force on the dispenser reduces the volume within the dispenser so as to dispense a portion of the contents of the dispenser through an opening in one end wall of the dispenser.

The dispenser of the present invention is compressed by encircling the dispenser with one hand and squeezing the dispenser, using a normal gripping motion. With the novel construction of the dispenser, large rapid changes in volume of the dispenser follow the squeezing. Also, as the dispenser is squeezed, not only is the volume within the dispenser reduced, but opposite ends of the dispenser rotate in opposite directions to provide twisting motions in the dispenser. Since the dispenser is operated with one hand, and since the operator uses the entire hand rather than just the fingers, the dispenser when being operated has a natural feel in the hand. Also, it is possible to apply much more pressure through the gripping motion of the hand rather than using only fingers. The plastic dispenser of the present invention also has a very pleasing, attractive and distinctive shape.

The deformable plastic dispenser of the present invention substantially takes the shape of a cylinder. In the particular embodiments described in this application, the dispenser substantially takes the shape of a right circular cylinder. The cylindrical wall, however, is formed of corrugated material. More specifically, the corrugations in the wall run in a diagonal direction from one end of the cylinder to the other. The ends of the dispenser are formed as rigid end walls. In a first embodiment of the invention, the end walls are flat, and holes are provided in one end wall so that a portion of the contents of the dispenser can be ejected from the dispenser through the holes to the outside. In a second embodiment of the invention, one end wall of the dispenser has a domed portion with a plurality of holes in the domed portion. This allows for greater dispersion of the contents of the dispenser. Also, one end wall of the dispenser can be formed to have a small nozzle with a very small hole so that the end wall acts as a spray nozzle. Another adaptation of the deformable plastic dispenser is to have one end wall contain a removable portion to allow for a refilling of the dispenser.

The deformable plastic dispenser of the present invention

2

tion can be used for liquid materials, such as deodorants or shampoo, or could be used for dry materials, for example, talcum powder. The invention will become clearer with reference to the following drawings wherein:

5 FIGURE 1 illustrates a first embodiment of the invention;

FIGURE 2 illustrates the operation of the invention, specifically with reference to the structure of the first embodiment shown in FIGURE 1;

10 FIGURE 3 illustrates a modification of the invention using a domed top;

FIGURE 4 illustrates another modification of the invention using a spray nozzle top; and

15 FIGURE 5 illustrates a refillable dispenser. In FIGURE 1 a plastic dispenser 10 substantially has the shape of a right circular cylinder. The cylindrical wall is formed of a series of upwardly extending parallel ridges having side walls 12 and 14. End walls 16 and 18 are connected and sealed to the cylinder. As shown in FIGURE 1, the end walls are flat. Holes 20 are placed in one end wall to allow the ejection of the contents of the dispenser. The dispenser is made of a tough, flexible plastic material which allows the flexing of the cylindrical wall but provides sufficient restoring force so that the dispenser 20 will return to its original shape.

25 FIGURE 2 illustrates the operation of the deformable plastic dispenser of the present invention. As can be seen in FIGURE 2, the dispenser 10 is gripped in a position intermediate the end walls by the user. The dispenser 10 is then squeezed, using a normal gripping motion of the hand, to collapse the corrugations or ridges formed in the cylindrical wall of the dispenser. The side walls 12 and 14 of the ridges are compressed toward each other so that the normal volume of the dispenser is reduced. In addition, the compression of the dispenser produces rotation at the outer ends of the cylinder. More specifically, the upper portion of the cylinder rotates in a direction as shown by arrow 22 and the lower end of the cylinder rotates in an opposite direction as shown by arrow 24. 30 The double rotation of the dispenser is helpful when the dispenser is used to eject dry materials such as powders, since the double rotation loosens the powders within the dispenser and prevents the powder from becoming caked in a single position. As the container is operated as shown in FIGURE 2, a portion of the contents of the container is ejected through the holes 20 in an upward direction as shown by the lines 26, due to the rapid reduction in the internal volume of the dispenser.

35 In FIGURE 3 a modification of the upper end wall of the plastic dispenser is shown which uses a domed top 100. The domed top 100 also provides a rigid end wall and includes holes 102 disposed through the domed top. The contents of the dispenser are ejected as shown by lines 104. As can be seen in FIGURE 3, the contents of 40 the dispenser are dispersed over a much broader area than from the dispenser of FIGURE 1.

45 FIGURE 4 illustrates another modification of the dispenser and shows an upper portion which has a spray nozzle 200 attached to one of the rigid end walls. This type of dispenser would be used to dispense liquid materials such as deodorants. A small hole 202 extends through the nozzle 200. As the dispenser is squeezed, the liquid material is forced through the small hole 202 and forms a spray, as shown at 204. It will be appreciated that the hole 202 may be made larger so as to allow for the dispensing of heavier liquids, such as shampoos, in a steady stream.

50 FIGURE 5 illustrates the dispenser constructed in accordance with the invention using a plug 300 inserted in the bottom end wall. The plug 300 is designed to be removable. For example, the plug can be screwed into the

bottom portion or can snap into the bottom portion. The use of the plug 300 allows the deformable plastic dispenser to be refillable and, therefore, reusable.

Since the deformable plastic dispenser of the present invention is formed of a substantially circular cylindrical shape, it can be very easily grasped in one hand. It is, therefore, not necessary to use two hands, or to use only the fingers to operate the dispenser. Also, since the dispenser is formed with diagonally disposed corrugations or ridges, a good surface is provided for gripping the dispenser, and the dispenser will not easily slip from the hand of the user. In addition, since the dispenser does have a good surface for gripping, it is possible for the user to exert very strong pressure on the dispenser, and since the collapsible corrugations or ridges allow for considerable reduction in volume, the contents of the dispenser can be ejected very easily. The deformable plastic dispenser has been illustrated with reference to particular embodiments, but it is to be appreciated that other adaptations and modifications may be made. Therefore, the invention is only to be limited to the appended claims.

What is claimed is:

1. A deformable plastic dispenser for dispensing a particular material housed within the dispenser, including: a cylinder having opposite ends and composed of flexible material having corrugations formed by first creases extending linearly in a diagonal direction along the entire distance between the opposite ends to define peaks in the corrugations and further formed by second creases extending linearly in the diagonal direction along the entire distance between the opposite ends to define valleys in the corrugations with first sides of the corrugations sharply sloping in a first direction between the first and second creases and with the second sides sharply sloping between the first creases in a second direction transverse to the first direction, first and second end walls made from a relatively rigid material and spaced from each other to enclose the opposite ends of the cylinder, the cylinder being responsive to forces applied to the cylinder at positions between the first and second end walls and circumferentially around the cylinder to obtain a folding of the first and second sides of the corrugations toward one another with the first and second creases as fulcrums to obtain a reduction in the volume enclosed by the cylinder and end walls and to obtain a rotation of the first and second end walls in opposite directions without substantially reducing the distance between the end walls and without deforming the end walls, and an opening through the first end wall for dispensing the particular material from the dispenser in accordance with the force applied to the cylinder.
2. The dispenser of claim 1 wherein the first end wall includes a plurality of holes.
3. A compressible flexible dispenser for dispensing a particular material, including: a pair of substantially circular end walls spaced from each other along a central axis and made from a relatively rigid material, and a cylindrical member having a wall interconnecting the end walls, the wall of the cylindrical member being formed of a relatively deformable material and being provided with series of corrugations defined by first corrugations having first sides sloping in a first direction and second sides extending from the first sides and sloping in a second direction transverse to the first direction and further formed by first creases defining first boundaries between the first and second sides and second creases defining second boundaries between the first and second sides, the first and second creases extending diagonally and linearly in a parallel relationship to one another along the entire distance between the first and second end walls, the

cylindrical member being responsive to forces applied to the cylindrical member at positions intermediate the end walls to obtain a collapsing of the first and second sides toward one another and a compression of the cylindrical member and rotations of each of the end walls in the pair in an opposite direction to the other end wall in the pair without substantially reducing the distance between the end walls and without deforming the end walls.

4. The dispenser of claim 3 wherein one of the end walls includes a domed outwardly extending portion and additionally includes a plurality of holes through the domed portion of the end wall.

5. The dispenser of claim 3 wherein the end walls in the pair are parallel to each other.

6. A deformable plastic container for dispensing a particular material, including:

a pair of end walls made from a relatively rigid material and disposed in spaced relationship along a central axis and having an opening through a first one of the end walls, and

a cylindrical member having relatively deformable properties and having a wall interconnecting the end walls to form with the end walls the container for the particular material, the cylindrical member being provided with a series of parallel creases extending linearly in a diagonal direction along the entire distance from one end wall in the pair to the other end wall in the pair to define corrugations, the cylindrical member being responsive to the application of compressive forces at positions intermediate the end walls to obtain the production of a compression of the side walls of the cylindrical member and rotations of the end walls in opposite directions without substantially reducing the distance between the end walls and without deforming the end walls to obtain a reduction in the volume of the container for an ejection of some of the particular material from the opening in the first end wall.

7. A deformable plastic container for dispensing a particular material, including:

a pair of end walls spaced from each other along a central axis and having one of the end walls formed as a spray nozzle, and

a cylindrical member having a wall interconnecting the end walls to form a container for enclosing the particular material, the wall of the cylindrical member being formed of corrugations defined by a series of parallel flexible upstanding creases extending in a linear direction on a diagonal basis from one end wall to the other end wall and with the upstanding creases separated by sharply sloping side walls to define the corrugations, the cylinder being responsive to forces applied to the cylindrical member at positions intermediate the end walls to obtain a folding of the side walls toward each other on the creases as a fulcrum for a corresponding reduction in the volume of the container and to obtain the application of forces to the particular material for an ejection of some of the particular material from the spray nozzle formed in one of the end walls without substantially reducing the distance between the end walls and without deforming the end walls.

8. A deformable reusable plastic dispenser for dispensing a particular material, including:

a cylinder having an annular surface and composed of flexible corrugated material having parallel creases extending diagonally along the annular surface of the cylinder and defining sharply sloping side walls between adjacent creases,

first and second end walls enclosing the opposite ends of the cylinder and defining terminations of the creases, the cylinder being responsive to forces applied at positions between the first and second end walls and circumferentially around the cylinder to

obtain a folding of the side walls of the cylinder toward one another on the creases as a fulcrum and to obtain a compression of the cylinder and a rotation of the first and second end walls in opposite directions without substantially reducing the distance between the end walls and without deforming the end walls, and

a portion of one of the end walls being removable to provide an opening in which to insert the particular

material within the space formed by the cylinder and the end walls.
